UNITED STATES PATENT OFFICE.

CHARLIE W. SCOTT, OF LINCOLNTON, GEORGIA.

PLIERS.

Application filed January 6, 1925 Serial No. 919.

To all whom it may concern:

Be it known that I, CHARLIE W. SCOTT, a citizen of the United States, residing at Lincolnton, in the county of Lincoln, State of Georgia, have invented certain new and useful Improvements in Pliers; and I do hereby declare the following to be a full, clear, and exact description of the invention, such as will enable others skilled in the art 10 to which it appertains to make and use the same.

This invention relates to new and useful improvements in tools, and particularly to pliers.

15 One object of the invention is to provide a tool of this character wherein the jaws are capable of great leverage, and firm holding ability.

Another object is to provide a tool of this 20 character wherein the jaws may be easily and quickly released from the work without the necessity of swinging the handles on their pivot.

Other objects and advantages will be apparent from the following description when taken in connection with the accompanying drawing.

In the drawing:

Figure 1 is a perspective view of a pair 30 of pliers made in accordance with the present invention.

Figure 2 is a perspective view of one of the members.

Figure 3 is a perspective view of another 35 of the members.

Figure 4 is a perspective view of the remaining member.

Referring particularly to the accompanying drawing, the pliers consist of the three 40 parts A, B, and C.

The part A is formed from a single piece of metal, and includes a body portion 10 having a vertical slot 11 formed throughout the greater part of its length. Formed on 45 one end of the body 10 is the jaw portion 12, into the inner end of which the slot 11 extends. In the end of the body, adjacent the jaw portion 12 there are formed the transversely alined openings 13 for the pivot 14. The other end of the body 10 diverges, as shown at 15, and formed transversely through this portion are the alined arcuate 50 slots 16. Beyond the divergent portion of the body there is formed an offset portion 17 which is bifurcated, as shown at 18, and

from this portion 17 there extends the handle shank 19.

Disposed longitudinally within the slot 11 of the body 10 is the shank portion 20, of the member B, one end of said shank being 60 formed with a jaw portion 21, which projects beyond the end of the body 10, in position to co-operate with the jaw 12. The other end of the shank 20 is formed with a fan-shaped portion 22, the curved edge of 65 which is provided with a series of rack teeth 23, said fan-shaped portion operating through the slot 11, within the divergent portion 15. The jaw-carrying end of the shank 20 is supported on the pivot 14. 70

Within the offset portion 17 there is disposed the forward end 24 of the handle shank 25, said end being in the form of a segmental gear 26, which meshes with the teeth 23. On the handle shank 25, adjacent 75 the toothed portion 26, there is formed a projection 27 which is arranged to be engaged by the thumb or finger of the hand of the operator who grasps the handle shanks 19 and 20. Disposed through the 80 center of the toothed portion 26 is a pivot 28, the opposite ends of which lie in the arcuate slots 16, whereby the said portion 26 is capable of pivotal movement, when in mesh with the portion 22, to cause the member B 85 to rock on its pivot and move the jaw 21 toward and away from the jaw 12.

Normally, when the handle shanks 19 and 25 are pressed toward each other, the member C slides forwardly until the ends of the 90 pivot 28 lie in the forward ends of the slots 16, whereby the action of the teeth of the portion or gear 26 operates upon the rack 22 to swing the portion B and move the jaws into engagement with a piece of work. 95 When it is desired to release the jaws from the work, the operator places the thumb of the tool gripping hand on the projection 27 and draws the member C inwardly through the hand, with the result that the pivot 28 100 will slide in the slots 16, thereby disengaging the member B from the rack of the member A. Upon placing the thumb against the projection 27, and pressing forwardly, the member C may be moved forwardly to engage the teeth of the gear 26 with the rack teeth 23. 105

What is claimed is:

1. A tool comprising a shank having a jaw and a handle, a second jaw movably 110

carried by the shank, and a second handle slidable into and out of operative engagement with the said second jaw.

2. A tool comprising a shank having a jaw on one end and a handle on the other end, a second jaw pivotally mounted on the shank for movement toward and away from the first jaw, and a second handle slidable on the shank into and out of operative engagement with the pivotally mounted jaw.

3. A tool comprising a member having a shank and a jaw, a member pivotally supported on the first member and having a jaw on one end and a rack on the other end, and an operating member pivotally and slidably mounted on the first member and having a toothed portion engaged with said rack for rocking the member first pivoted and the jaw carried thereby, and for slid-
20 able movement longitudinally of the shank member to engage and disengage its toothed portion with respect to the said rack.

4. A tool comprising a member having a jaw and a central longitudinal slot, a jaw carrying member in said slot and pivotally mounted on said member, the jaw carrying

member having an arcuate rack, and an operating member pivotally supported on the first member and having a gear portion engaged with the said rack, said operating member having a pivot slidably engaged with the first member whereby to permit movement thereof into and out of engagement with said rack.

5. A tool comprising a member having a longitudinal slot and a jaw on one end and a handle shank on the other end, a jaw carrying member pivotally supported in said slot and having an arcuate rack on one end, said first member having transversely alined arcuate slots, an operating member in said slot and having a pivot engaged in said slots and a handle shank, the pivotal portion of the operating member having a gear meshing with said rack, and a projection arranged to be engaged by the thumb of the operator for moving the operating member into and out of engagement with said rack.

In testimony whereof, I affix my signature.

CHARLIE W. SCOTT.
